UNITED STATES PATENT OFFICE.

JOHN ANTHONY DE LUISI, OF CINCINNATI, OHIO, ASSIGNOR TO HIMSELF AND MERRICK LINLEY BATES, OF CINCINNATI, OHIO.

DESIGN FOR A FINGER-RING OR SIMILAR ARTICLE.

No. 39,623.

Specification for Design.

Patented Oct. 20, 1908.

Application filed July 20, 1908. Serial No. 444,549. Term of patent 14 years.

To all whom it may concern:

Be it known that I, JOHN ANTHONY DE LUISI, a citizen of the United States, residing at Cincinnati, in the county of Hamilton and State of Ohio, have invented a new, original, and ornamental Design for Finger-Rings or Similar Articles, of which the following is a specification, reference being had to the accompanying drawing, forming part thereof.

The figure is a perspective view of a finger-ring, showing my new design.

I claim—

The ornamental design for a finger-ring, or similar article, as shown.

JOHN ANTHONY DE LUISI.
